W. SCHNEIDER.
CONDIMENT HOLDER,
APPLICATION FILED APR. 5, 1920.

1,362,442.

Patented Dec. 14, 1920.

Inventor.
William Schneider.

by Lacy Lacy, Reg'd.

UNITED STATES PATENT OFFICE.

WILLIAM SCHNEIDER, OF VERDON, NEBRASKA.

CONDIMENT-HOLDER.

1,362,442.

Specification of Letters Patent. Patented Dec. 14, 1920.

Application filed April 5, 1920. Serial No. 371,299.

To all whom it may concern:

Be it known that I, WILLIAM SCHNEIDER, a citizen of the United States, residing at Verdon, in the county of Richardson and State of Nebraska, have invented certain new and useful Improvements in Condiment-Holders, of which the following is a specification.

This invention relates to improvements in 10 condiment holders and more particularly to a combined salt and pepper shaker.

An important object of this invention is to provide a condiment holder having a centrally arranged partition thereby forming 15 separate compartments adapted for the reception of salt and pepper or other condiments which may be discharged separately.

A further object of this invention is to 20 provide a condiment holder having a plurality of compartments adapted to receive various condiments and novel means whereby the condiment in one of the compartments may be prevented from being discharged while the condiment in the other 25 compartment is being discharged.

A further object of the invention is to provide a condiment holder which is neat in appearance, desirable in use and cheap to manufacture.

30 Other objects and advantages of the invention will be apparent during the course of the following description.

In the accompanying drawing forming a part of this application in which like numerals are employed to designate like parts through the same:

Figure 1 is a side elevation of a condiment holder embodying the invention,

Fig. 2 is a central vertical section through 40 the same in use, and

Fig. 3 is a horizontal section taken on the line 3—3 of Fig. 2.

In the drawing wherein for the purpose of illustration is shown a preferred embodiment of the invention, the numeral 5 generally designates the improved condiment holder which may be formed of any desired material such as glass, metal or celluloid.

As illustrated in Fig. 2, the body of the 50 holder is provided with a centrally arranged vertically disposed partition 6 which extends from its bottom to its top thereby forming compartments 7 and 8 adapted for the reception of such condiments as pepper and salt. The upper portion of the body is provided with a pair of outwardly directed

necks 9 having their outer portions externally screw threaded for engagement with the apertured covers or caps 10. It will be noted that when the condiment within one of the compartments is being discharged, the discharge neck of the other compartment is facing upwardly so that the condiment within that compartment is prevented from being discharged. To further provide means whereby but one condiment may be discharged at a time, I have secured a pair of downwardly extending baffle plates 11 to the partition 6 on opposite sides of the same. The inner or upper edges of the baffle plates join the partition at the top of the condiment holder and the lower edges of the baffle plates are arranged in spaced relation to the outer sides of the necks 9, so as to provide restricted discharge passages 75 for the condiment. A second set of baffle plates 12 are secured to the partition 6 below and in spaced relation to the baffle plates 11 and coöperate with the baffles 11 in preventing more than one condiment being discharged from the holder at a time.

With reference to Fig. 2, it will be noted that the outer side of each compartment is curved so that the upper portion of the same is reduced at the lower edge of the adjacent baffle 12. Further each baffle is curved to conform to the curvature of the outer wall of each compartment so that when the holder is in position to discharge the condiment from one compartment, the lower 90 baffle 12 of the other compartment will coöperate with the adjacent portion of the partition 6 for confining the condiment in that compartment in the lower portion of the same. In other words, each baffle 12 is curved and is disposed in the arc of the same circle as the outer side of the compartment within which it is arranged so that the condiment within the upper portion of that compartment will be directed to a high degree between the baffle 12 and the adjacent portion of the partition. Any part of the granular material which may pass beyond the lower baffle 12 will be engaged by the upper baffle 11 so as to prevent its passage through the perforated cap 10. In addition to confining the granular material in one of the compartments to the lower portion of the same, the baffles 11 and 12 serve as a means for disintegrating the condiment should the same become lumpy. Obviously the shaking of the holder during the use of

the same will cause any lumps which may exist to abut the baffles and thereby be broken up. Assuming that salt is placed in the compartment 8 and that pepper is placed 5 in the compartment 7, the salt may be discharged by lowering the discharge neck of the compartment 8 and then shaking the holder. With the holder in a downwardly inclined position, the pepper within the 10 compartment 7 will be directed between the baffle 12 and the adjacent portion of the partition 6. As the curvature of the baffle 12 increases the restraining capacity of the same, but a small portion of the pepper will 15 be permitted to pass into the upper portion of the compartment. However, any pepper which does pass the baffle 12 will be engaged by the baffle 11 and will be prevented from being passed out through the cap 10.

20 It is to be understood that the form of the invention herewith shown and described is to be taken as a preferred example of the same and that such minor changes in arrangement and construction of parts may 25 be made as will remain within the spirit of the invention and the scope of what is claimed.

Having thus described the invention, what is claimed is:

30 1. A condiment holder including a body, a centrally arranged partition disposed within the body thereby forming a pair of compartments, the upper portion of said body being provided with a pair of outwardly directed necks in communication with said compartments, said compartments having their outer sides curved, and a pair of transversely curved baffles secured to said partition and having the same curvature as 35 the outer side walls of said compartments, said baffles and the curved outer walls of said compartments being disposed in the arc of the same circle, whereby the material within one of the compartments is directed 40 between one of said baffles and the adjacent portion of said partition when the holder is 45

inverted for discharging the material from the other compartment.

2. A condiment holder including a body having its upper portion provided with a 50 pair of diagonally extending necks, apertured caps secured to the upper portions of said necks, a partition extending from the bottom to the top of said body thereby forming a pair of compartments, a pair of baffles secured to the upper end of said partition 55 and extending downwardly from the same, each compartment having its outer side wall curved inwardly for forming a reduced passage between the upper and lower end of 60 each compartment, and a second pair of baffles secured to said partition below the first named pair of baffles and being disposed in the arc of the same circle as the curved outer walls of the compartments 65 whereby the material within one of the compartments is directed between one of the second named baffles and the adjacent portion of said partition.

3. A condiment holder including a body, 70 a partition arranged within the body thereby dividing the same into a pair of compartments, the outer side walls of said compartments being curved for providing a restricted passage between the upper and lower portions 75 of the compartments, and curved baffles secured to said partition at the restricted portions of said compartments and disposed in the arc of the same circle as the curved outer walls of said compartments 80 whereby the material within one of the compartments is directed between the curved baffle in that compartment and the adjacent portion of said partition when the holder is inverted for discharging material from 85 the other compartment.

In testimony whereof I affix my signature.

WILLIAM SCHNEIDER.
